(57) CLAIM

The ornamental design for a pendant, as shown and described.

DESCRIPTION

FIG. 1 is a perspective view of a pendant showing our new design.

FIG. 2 is a front thereof;

FIG. 3 is a rear view thereof;

FIG. 4 is a side view thereof;

FIG. 5 is an opposite view thereof;

FIG. 6 is a top view thereof; and,

FIG. 7 is a bottom view thereof.

The broken lines showing a chain represent environmental matter and the remaining broken lines represent portions of the pendant that form no part of the claimed design.

1 Claim, 2 Drawing Sheets

FIG. 4

FIG. 5

FIG. 6

FIG. 7
